UNITED STATES PATENT OFFICE.

BURGESS SMITH, OF MACON, GEORGIA, ASSIGNOR TO THE E. & H. T. ANTHONY & COMPANY, OF NEW YORK, N. Y.

FLASH-LAMP.

SPECIFICATION forming part of Letters Patent No. 505,780, dated September 26, 1893.

Application filed June 27, 1893. Serial No. 478,961. (No model.)

To all whom it may concern:

Be it known that I, BURGESS SMITH, a citizen of the United States, and a resident of Ma-
5 con, in the county of Bibb and State of Georgia,
have invented a certain new and useful Flash-
Lamp, of which the following is a specifica-
tion.

My invention relates to a new and improved
flash lamp for photographic purposes.

10 The essential features of the invention are
its simplicity, its compactness, its cheapness,
its efficacy, and the fact that it may be loaded
while the alcohol is burning.

In the drawings hereof: Figure 1, illustrates
15 a plan view of a sheet of metal from which I
construct the major portion of the device. Fig.
2, is a perspective showing the device as com-
pleted, with the exception that the box which
holds the magnesium or other inflammable
20 powder is not upon the machine. Fig. 3, illus-
trates the device complete and duly "set" for
making a flash.

A is a piece of metal preferably spring
brass. Other metal however may be em-
25 ployed.

B, B are two flanges, which are bent at right
angles to the part marked A, so as to form
two side pieces to stiffen the structure.

C is an end piece or flange, which is bent
30 in substantially the same manner that the
parts B, B are, and in the constructed ma-
chine it makes a ledge against which the
spring which throws the magnesium strikes
when released by the trigger.

35 D is a tongue-like part, which is cut out
from the face of the piece A, and is bent
in the form shown in Figs. 2 and 3, so as to
make a clip or spring clamping device where-
40 by the lamp can be fastened to the edge of a
mantel-piece or table or other suitable ledge.

E is a portion of the piece of metal A, which
is bent underneath and backwardly relative
to the part A on the dotted line F.

G is an enlarged end portion of the part E,
45 which has side pieces or flanges H, H, which
are turned over upon the part G, as best
shown in Fig. 2, so as to form clamping ways
to hold the box which contains the magnesium
powder.

I is a spring tongue cut from the part G, 50
which presses against the under side of the
box which holds the magnesium powder,
whereby it is held firmly in place. This box
is shown at J, Fig. 3. It is soldered or other-
wise fastened to a plate K, which slides un- 55
derneath the flanges H, H.

L is a trigger which is slotted as at M and
has a rectangular forward end N. It is fas-
tened to one of the side pieces B of the frame
by headed pins O, O, which play through the 60
slot, so that the trigger has longitudinal move-
ment. It is also provided with a thumb but-
ton P, so that it may be projected forwardly,
and a cord Q, which passes through an eye
R, which serves to pull it rearwardly to re- 65
lease the spring which supports the magne-
sium box.

S is a ring of wire, which passes through
and is supported by two eye or like parts, T,
T, which are punched out from the part A, so 70
that the ring can be turned within these eyes.
The arc of the ring between the eyes, is, of
course, flattened to permit of its being turned
upwardly as indicated by the arrow. The
ring S is wrapped about with any suitable 75
cloth-like material adapted to be saturated
with alcohol or equivalent inflammable sub-
stance. The ring may be composed of a wire
gauze structure the interior of which is filled
with absorbent material. 80

The operation is as follows: The ring S is
saturated with the inflammable liquid. The
little box J, which contains the magnesium or
other inflammable powder is slipped from
under its confining flanges H, H, and is filled 85
with magnesium powder. It is then replaced
and the spring E depressed by hand into the
position shown in Fig. 3, and the trigger L is
pushed forwardly until the end of the rect-
angular part N engages with the upper sur- 90
face of the platform upon which the box rests.
Then the alcohol is lighted and burns in ring
form entirely around the ring S. When de-
siring to make the exposure, the cord Q is
pulled which withdraws the trigger, the spring 95
E then immediately exerts its power and
claps itself up against the flange C—in other
words, moving from the position shown in Fig.

3, to that shown in Fig. 2. The sudden stopping of the spring projects the magnesium powder in the box upwardly and through the ring of flame. It of course instantly flashes and makes a very superior light.

5 My device, as before stated may be attached to the top of a table, mantelpiece or other structure, in which event, I find it convenient to employ a thumb-screw U, shown in Fig. 2, 10 which passes upwardly through a threaded opening V, which has preferably a bushing threaded on its interior, and which passes through the spring E and the top plate A of the device. This gives strength also to the 15 spring. I do not show this thumb screw in Fig. 3, because I make the threads in the bushing V of such size as that they may engage with a suitably threaded stem on a tripod when desired. In this way the flash lamp can be attached to a tripod, the thumbscrew U being 20 temporarily removed. Although I prefer not to light the alcohol until the magnesium powder is in place and the spring set, nevertheless it is possible, and frequently very 25 convenient to load the device and use it without blowing out the alcohol; in so doing the ring is turned upwardly in the direction of the arrow (see Fig. 2) so as to remove the flame as far as possible from the powder, and 30 after the device is all arranged and the spring set, then the ring S may be carefully turned down into position, without danger of igniting the powder.

It will be evident to those who are familiar 35 with this art, that modifications may be made in the details of construction of the device, and still the essential features of my inven-

tion be employed. I do not therefore limit myself to the details.

I claim—

1. The combination in a flash lamp of a 40 spring, a receptacle for the powder supported on a spring, a trigger to maintain the spring under tension, and a lamp, substantially as set forth.

2. The combination in a flash lamp of a 45 spring, a receptacle for powder, supported upon the spring, a trigger to hold the spring under tension, a ring placed adjacent to the spring, adapted to be used as a lamp, the 50 parts being arranged in such manner that the powder is thrown by the spring through the ring, substantially as set forth.

3. The combination in a flash lamp of a 55 spring, a receptacle for the powder, supported upon the spring, a trigger to hold the spring under tension, a pivoted or hinged ring placed adjacent to the spring, adapted to be used as a lamp, and to be swung away from the magnesium powder, substantially as set forth.

4. The combination in a flash lamp, of a 60 frame having a clip or clamping device on one side, a spring on the other side and a ring-shaped lamp at or near one end, the free end of the spring being practically coincident 55 with the center of the ring, substantially as set forth.

Signed at Macon, in the county of Bibb and State of Georgia, this 20th day of June, A. D. 1893.

BURGESS SMITH.
